TREATING PROCESS

Mead Cornell, Cleveland, Ohio, assignor to The Cornell Machine Company, Cleveland, Ohio, a corporation of Ohio

Application August 17, 1938, Serial No. 225,356

1 Claim. (Cl. 259—96)

This invention relates, as indicated, to treating process for the particular treatment of materials and is an improvement of the process and apparatus of my prior Patent No. 2,042,880.

5 It will be observed that the apparatus and process of my said prior patent is characterized, in that the material to be mixed or treated is impounded centrally of a rotating member and then centrifugally attenuated as a continuous 10 film over said member while mechanically supported on one side only, and whereby an intimate and thorough mixing and treating of the work material is effected.

The present invention is directed to an improvement in such process and apparatus whereby the components, or at least certain of them which are to be mixed or otherwise combined in a treating step, are separately attenuated into continuous films and such films then brought together to the accomplishment of the desired mixing or treating. It is, therefore, a principal object of my invention to provide an improved apparatus and process of the character described. Other objects of my invention will appear as the 25 description proceeds.

To the accomplishment of the foregoing and related ends, said invention then consists of the means hereinafter fully described and particularly pointed out in the claim. The annexed 30 drawing and the following description setting forth in detail certain means and one mode of carrying out the invention, such disclosed means and mode illustrating, however, but one of various ways in which the principle of the invention may 35 be used.

In said annexed drawing:

Fig. 1 is a vertical sectional view partially in elevation of one form of the apparatus embodying the principles of my invention; and Fig. 2 is 40 a transverse sectional view of the apparatus illustrated in Fig. 1, taken on a plane substantially indicated by the line 2—2.

Referring now more specifically to the drawing and more especially to Fig. 1, the apparatus comprising my invention includes a housing generally indicated at 1, provided with a bottom 2, a cover plate 3, and supporting legs 4. Body 1 is preferably cylindrical in form and the bottom 2 and top 3 are preferably curved in the manner illustrated, so that when the process is carried on under a vacuum or elevated pressure, the ends and side wall of the container housing the apparatus where the process is performed will be 50 mechanically strengthened against failure.

5 Supported on the cover plate 3 is a housing member generally indicated at 5, which is provided with anti-friction bearings 6 and 7 rotatably supporting a vertically disposed hollow shaft 8. The hollow shaft 8 is at its lower end supported in an anti-friction bearing 9 carried by a bracket member 10. The bracket member 10 is supported from the side wall 1 by means of legs 11 and 12 and the supply pipe 13 which also serves 10 as a supporting leg.

The upper end 14 of the housing 5 carries an electric motor 15 which drives the shaft 8 through the flexible coupling 16.

15 Supported in spaced relation on the hollow shaft 8 are oppositely disposed substantially conform discs 17 and 18, preferably of different diameters and so arranged that the peripheral edge of the smaller disc lies in a plane which intersects the work surface of the larger disc. While 20 in the drawing the larger disc has been illustrated as the upper one and the smaller disc illustrated as the lower one, nevertheless it is within the contemplation of my invention to reverse the 25 position of these parts.

26 Mounted on the hollow shaft 8 and capable of movement axially with respect thereto, and positioned between the discs 17 and 18, are spreader members 19 and 20. These spreader members are annular in form, tapering to a rather sharp 30 edge at their peripheries, and are resiliently 35 forced apart and into engagement with their associated discs by means of a spring 21. One of the spreader members 19 or 20 may be provided with an anti-friction bearing, such as 22, through which the spring 21 acts so as to permit free 40 relative rotation between the spreader members, if this should be necessary or desirable, since generally the spreader members 19 or 20 are capable of rotation relative to the hollow shaft 8.

The hollow shaft 8 is provided with two plugs 45 22 and 23 closing the passage therethrough at the points where these plugs occur.

In the regions respectively generally indicated by the reference characters 24, 25 and 26, the 45 wall of the hollow shaft is provided with a plurality of openings therethrough for the purpose hereinafter more fully explained.

The housing 5 is enlarged, as indicated, around the area 24 of the shaft 8, and the anti-friction 50 bearings 6 and 7 are of the type providing a fluid seal. A supply conduit 27 is connected to the housing 5 for the purpose of introducing some of the material to be treated to the apparatus.

55 Interiorly of the housing 1 and supported from the cover plate 3 by suitable depending brackets

3a, there is provided an annular deflecting ring 28 adjacent the peripheral edge of the larger disc. A discharge conduit 29 is connected to the bottom 2 for the purpose of withdrawing from the apparatus the material which has been treated. A conduit 30 is connected to the top 3 of the apparatus through which the space defined by the housing 1 may be evacuated so that the treating process may be carried on in a vacuum or alternatively a treating fluid, such as a gas under pressure may be introduced to the apparatus through the conduit 30.

The function of operation of the above described form of apparatus is briefly as follows:

15 The motor 15 is energized driving the discs 17 and 18 and their associated spreader members 19 and 20. A portion of the material to be treated, or more particularly one component of the desired ultimate mixture, is introduced to the apparatus through the conduit 27 and another portion of the material is introduced to the apparatus through the conduit 13. The material which flows through the conduit 27 passes into the space around the hollow shaft 8 defined by 25 the housing 5. It flows through the openings 24 downwardly through the shaft 8, and is discharged through the openings 25 into the space between the spreader member 19 and its associated disc 17. Pressure of the material in this 30 last defined space causes the spreader member 19 to move away from its associated disc 17, and since the latter is rotating at a relatively high speed, the material thus liberated will pass outwardly over the under face of the disc 17 in the 35 form of a highly attenuated continuous film which is mechanically supported on one side only.

Similarly, that portion of the material which is introduced to the apparatus through the conduit 13 passes upwardly through the lower end of 40 the hollow shaft 8 and is discharged through the openings 26 into the space between the spreader member 20 and its associated disc 18, from whence it flows outwardly over the upper surface of the disc 18 in a highly attenuated continuous film 45 mechanically supported on one side only.

It is important to note that in carrying out the 50 operation of the apparatus in the preferred manner in practicing the process of my invention, the outer periphery of the disc 18 is spaced sufficiently from the lower surface of the disc 17, so as to, in no way, interfere either with the passage of the thin film outwardly over the disc 17 or the discharge of the thin film from the periphery of the disc 18. The film which flows outwardly 55 across the under face of the disc 17 from the central portion thereof therefore passes undisturbed past the peripheral edge of the disc 18. The continuous film which is discharged from the peripheral edge of the disc 18, however, flows on to the under face of the disc 17, due to the 60 overlapping arrangement of the discs, and is there instantly and completely intermingled with the original film generated on the disc 17. While not illustrated in the drawing, it is within the 65 contemplation of my invention to alter the slope of the active face of the larger disc at the point where the continuous film from the smaller disc is discharged thereto, so as to compensate for the increased thickness in film, if this should be 70 necessary in treating particular types of materials. Thus, the disc 17 in the annular area between its peripheral edge and the area where the film from the smaller disc 18 is delivered thereto, may be curved outwardly at a different 75 and preferably a greater angle than the central

portion of the disc 17. If the mixing of the two attenuated films is to be increased, or if the film from the smaller disc is of such a nature that it will not be picked up readily by the larger disc, then the outer peripheral area of the larger disc just defined may be disposed at an angle more acute to the axis of its rotation.

The mixed and/or treated material is discharged from the peripheral edge of the disc 17 in the form of a continuous film onto the deflecting ring 28 which deflects such continuous film, without breaking it up, downwardly against the side wall 1 so that the film may flow downwardly into the collecting chamber at the bottom of the apparatus.

In making a mixture of two components, or in treating one material with another, such two components will be respectively admitted to the apparatus through the conduits 13 and 21, to be later brought together in the form of highly attenuated continuous films in the manner above described. When a mixture of more than two components is to be made, or if, for example, a mixture is to be treated by means of an additional component, such groups of components 25 may be respectively admitted to the apparatus through the conduits 13 and 27. If the treating process carried out by the apparatus involves a reaction, then generally the respective phases contributing to such reaction will be admitted 30 through the separate conduits 13 and 27, respectively, and not brought together until they have been attenuated, as described.

The above described apparatus is particularly suitable for use in carrying out a process of 35 treating materials where it is essential that there be a complete dispersion of one component in the other immediately the components are brought together, so as to preclude against over-treating certain portions of one or the other component 40 which might result if there was even slight delay in effecting complete dispersion.

While only one pair of discs, i. e., a large disc and a smaller disc, has been illustrated, it is nevertheless within the contemplation of my invention to employ more than two such discs in carrying out my process if it should be desirable to attenuate more than two components before bringing them together. This may be readily accomplished by employing either an additional 45 smaller disc, the peripheral edge of which will discharge onto the active surface of the larger disc, or by the use of a disc larger than 17, for example, onto which the latter disc will discharge.

The apparatus and process comprising my invention are adapted to a wide variety of uses, 55 among which may be named the following:

The blending or mixing of oil stock such as 60 petroleum oils; the mixing of liquids and slurries such as, for example, treating a fatty oil with a slurry of treating clay; the alkali treatments of fatty oils for the purpose of neutralizing the free fatty acids contained therein; the acid treatment of resins, etc.

The alkali treatment of fatty oils for the purpose of saponifying the free fatty acids contained 65 therein is an example of the type of process wherein the separate components of phases of the reaction are attenuated before being brought into intimate contact with each other. The present apparatus may also be used for the purpose of chlorinating or similarly treating liquids capable of absorbing or having chlorine combined therewith. For example, if a liquid material is 70 to be chlorinated, the same is introduced in the 75

5 manner described to the upper disc and the chlorine, preferably in liquid form, is introduced to the lower disc, so that a finely attenuated film of liquid chlorine is introduced to the liquid film to be chlorinated. Inasmuch as the film of the material being treated extends in an unbroken film from the edge of the upper disc to the side wall of the container, any gas introduced in the lower part of the apparatus such as by direct 10 introduction or vaporization, as by vaporization of the liquid chlorine, must pass upwardly through such film in passing to the escape pipe 38.

15 The described apparatus is particularly useful for the acid treating of resins, where, unless practically instantaneous and complete dispersion of the acid in the resin is effected, the former will have a tendency to scorch the latter. It will be observed by the use of the present apparatus, the 20 acid being attenuated by the lower disc and discharged onto the resin film of the upper disc is brought into intimate contact only with that portion of the resin which the acid is designed to treat.

25 In case the apparatus is employed for the purpose of carrying on an exo-thermic reaction, the reaction, it will be observed, takes place at the

very outer periphery of the upper disc and is immediately discharged against the side wall 4 of the container and in order to control the temperature of the reaction, such side wall may, therefore, be cooled by suitable means such as 5 a brine jacket.

10 Other modes of applying the principle of my invention may be employed instead of the one explained, change being made as regards the means and the steps herein disclosed, provided those stated by the following claim or its equivalent be employed.

I, therefore, particularly point out and distinctly claim as my invention:

15 The method of mixing two liquid bodies which comprises the steps of maintaining an impounded quantity of each such body respectively centrally of separate rotating members, radially displacing each of said bodies into separate continuous films respectively supported on one side only on 20 said rotating members, centrifugally attenuating said separate films, merging said separate continuous films into a merged continuous film, centrifugally attenuating said merged film and then collecting said attenuated merged film.

25

MEAD CORNELL.
